UNITED STATES PATENT OFFICE.

REINERT HANSEN, OF FRANKFORD, PENNSYLVANIA.

LETTERING-GUIDE.

No. 835,680.

Specification of Letters Patent.

Patented Nov. 13, 1906.

Application filed June 21, 1905. Serial No. 266,263.

To all whom it may concern:

Be it known that I, REINERT HANSEN, a citizen of the United States, residing at Frankford, county of Philadelphia, and 5 State of Pennsylvania, have invented a certain new and useful Improvement in Lettering-Guides, of which the following is a specification.

My invention relates to a new and useful improvement in lettering-guide, and has for its object to provide a device which will do away with the tedious and difficult work of constructing the letters and words to be written on typographic, architectural, mechanical, or other drawings, and mechanically to obtain perfect lettering on plans in a fraction of the time usually employed for their construction by the old methods.

With these ends in view this invention 20 consists in the details of construction and combination of elements hereinafter set forth and then specifically designated by the claims.

In order that those skilled in the art to 25 which this invention appertains may understand how to make and use the same, the construction and operation will now be described in detail, referring to the accompanying drawings, forming a part of this specification, in which—

Figure 1 is a plan view of one of the type-plates used in my invention; Fig. 2, a cross-section of the same on the line 2 2 of Fig. 1; Fig. 3, a plan view of one of the end weights 35 used in my invention; Fig. 4, a cross-section of Fig. 3 on the line 4 4 of Fig. 3; Fig. 5, a plan view of the type-holder, a portion of the same being broken away to shorten it; Fig. 6, a cross-section of the holder, taken on the 40 line 6 6 of Fig. 5; Fig. 7, a perspective view of my invention, showing how a pantograph is used in connection therewith.

My letter-guide is adapted to be used in connection with a pantograph, and each letter or character is formed on a separate plate A, the outlines of the letter or character being depressed in the upper surface of the plate, as represented at B, and the tracing-point is adapted to travel in the groove D, 45 forming the outlines of the letter or character represented upon the plates A. These plates are held within a holder C and are held in alinement by the upturned edges D², there being one character or letter to each 50 plate A, and these plates are made of such a width as to properly space the letters, the

letters being placed side by side between the upturned edges D² of the holder and resting upon the flat bottom plate D' of the holder.

E designates weights, also adapted to fit 60 between the upturned edges D² of the holder, and there are two of these weights, which are adapted to be forced against the end type-plates, and thus hold all of the type-plates in contact with one another. The holder is 65 provided with a series of holes F, formed through the bottom plate D', these holes all being in a straight line, and a line G is drawn upon the top of the bottom plate D' longitudinally, and this line is in alinement with 70 the center of the holes F. Thus the holder can be placed upon a straight line upon the plan, as the line drawn upon the plan can be viewed through the openings F, and the line represented upon the holder can be 75 placed in alinement at each end with the line upon the plan, and thus the reproduction of the letters in the holder will be upon a straight line. Thus in order to letter any drawing it is only necessary to select the 80 proper type-plates, place them in the holder, force the weights E up against each end of the type-plates, then secure the holder in the proper position, and then by using a pantograph the tracing-point need only be caused 85 to follow the outlines of the letters or characters, and said letters or characters will then be reproduced upon the drawing either enlarged or reduced, as occasion may require. These letters may either be upon a slant, as 90 shown in Fig. 7, or the sides may be made vertical, as shown in Fig. 1. When the letters are slanted, of course the contacting edges of the weights E will also be slanted to correspond; but when the letters are straight, as 95 shown in Fig. 1, the contacting edges of the weights will also be straight or vertical.

Of course I do not wish to be limited to the exact construction here shown, as slight modifications could be made without departing from the spirit of my invention.

Having thus fully described my invention, what I claim as new and useful is—

1. In a device of the character described, the combination of a pantograph, with a plurality of type-plates all of the same length having characters or letters represented upon the upper surface thereof, the outlines of these characters or letters being formed by depressed grooves in which the tracing-point 105 of the pantograph is adapted to travel, a holder consisting of a flat plate provided

upon each side with upturned edges between which the type-plates are adapted to fit, two weights fitting between the upturned edges of the holder and adapted to be forced 5 against each end of the row of type-plates and hold the same in position, the bottom plate of the holder being provided with a series of openings or holes formed through the same, all arranged in a straight line, a line 10 drawn upon the upper surface of the bottom plate longitudinally and intersecting all of the holes on the same plane, as and for the purpose specified.

2. In combination, a holder having opposite edges provided with flanges, plates 15 adapted to fit between the flanges of the holder, means for holding the plates against

movement, said holder being provided with a series of perforations in alinement.

3. In combination, a holder having opposite edges provided with flanges, plates adapted to fit between the flanges of the holder, means for holding the plates against movement, said holder being provided with a series of perforations in alinement, said 20 holder having a line thereon intersecting the openings on the same plane.

In testimony whereof I have hereunto affixed my signature in the presence of two subscribing witnesses.

REINERT HANSSEN.
